UNITED STATES PATENT OFFICE.

EDWARD W. DUGDALE, OF KEARNEY, NEW JERSEY.

DOORS FOR A CHUTE OF A DUMB-WAITER, ELEVATOR, OR THE LIKE.

1,133,794.

Specification of Letters Patent. Patented Mar. 30, 1915.

Application filed March 24, 1914. Serial No. 826,878.

To all whom it may concern:

Be it known that I, EDWARD W. DUGDALE, a citizen of the United States, residing at Kearney, in the county of Hudson, State of New Jersey, have invented new and useful 5 Doors for a Chute of a Dumb-Waiter, Elevator, or the like, of which the following is a specification.

My invention consists of a dumb waiter, 10 elevator or the like provided with doors leading to the shaft or chute of the same, said doors being adapted to be operated by each other; so as to be opened and closed simultaneously, and mounted in novel 15 frames formed of members preferably of metal, the device in its entirety being ready to be set up at the place of the chute which said doors are to occupy, and other details are provided, the construction and operation 20 of which being hereinafter set forth.

The invention is satisfactorily illustrated in the accompanying drawing, but the important instrumentalities thereof may be varied, and so it is to be understood that 25 the invention is not limited to the specific details shown and described.

Figure 1 represents a front elevation of the portion of a dumb waiter embodying 30 my invention. Fig. 2 represents a rear view thereof partly sectional. Fig. 3 represents a vertical section on line $x-x$ Fig. 1. Fig. 4 represents a horizontal section on line $y-y$ Fig. 1. Figs. 5 and 6 represent partial vertical sections and elevations of detached 35 portions.

Similar numerals of reference indicate corresponding parts in the figures.

Referring to the drawings, 1 designates 40 an exterior frame which is seated in a wall of a basement or apartment, and 2 designates an interior frame therein. The frame 1 consists of the angular side stiles or pieces 3, the lintel 4, and the sill 5, said members being firmly connected with each other.

The frame 2 consists of the channeled side 45 stiles 6, the upper cross bar 7, the shelf 8, said sill and cross bar being firmly connected with said side stiles 6 and the latter being firmly connected at their ends respectively with said lintel 4 and the sill 5 of the exterior frame and intermediate of their ends by the braces 9. The side stiles 6 are separated from the side stiles 3, forming the runways 10 for the occupation and passage 50 of certain members as will be herein-after specified. The side stiles 6 form ver-

tically-extending channel-shaped guides for the doors 11 and 12 which are placed below the other and have their sides freely fitted in the reveals of the side stiles 6 of 55 the inner frame so that said doors are adapted to rise and fall as sashes whereby they may be brought together to close the inlet and outlet space or shaft of the dumb waiter and separated to open the same. 55

Attached to the lower end of the upper door 11 are the chains 13 which pass therefrom as sash cords through openings 13^x in the side stiles of the inner frame and over pulleys 14, the latter being connected with 70 said side stiles and occupying the runways 10 a portion of said chains also entering said runways and being connected with the ears 15 which project from the upper ends of the lower door 12 through the openings 75 15^x in the side stiles 3 into said runways 10 and are movable in the latter with said chains. In order to attach said chains to the lower ends of the upper door, I employ the hooks 16 secured to the upper door and 80 engaging the lower links of said chains and adjacent portions of said door, and in order to permit the play of said portions of the chains within said side stiles said door has projecting laterally therefrom the bars 17 85 which freely occupy the spaces between the sides of the door and the sides of the stiles 6 of the interior frame, said spaces forming runways 18 for said portions of the chains, said bars also serving to guide the upper 90 door in said stiles and preventing lateral motions and rattling of said door.

In order to connect the chains 13 with the ears 15, the lower ends of the former are attached to the eye bolts or screw rods 95 19, the latter being adjustably fitted in said ears and retained in position by the nuts 20, on opposite sides of said ears, as most plainly shown in Fig. 5.

It will be seen that when the doors are 100 to be opened to admit access to the adjacent portion of the shaft of the dumb waiter, the upper door is raised when owing to the chains 13 being connected to the same and the lower door, the latter is caused to descend, thus separating the doors and consequently opening the same. By lowering the upper door, the lower door will be raised, thus bringing the doors together and so closing them, it being seen that the frame 110 110 is of length vastly greater than the height of the two doors when in closed position,

hence there is an unoccupied space above the upper door, and a similar space below the same. These spaces constitute pockets the upper one of which receives the upper door when opened, and the lower one of which receives the lower door when opened, the pockets thus being within the frame and not entering the dumb-waiter shaft.

- 10 The frames, doors and other appurtenances of the device are formed of metal which are light, strong, durable and fire-proof and the bottom of the frame will be on the floor line of a basement or apartment, so that the doors will be sufficiently above 15 said line so as to be convenient of access for operation thereof, it being evident that either door may be operated to cause motion of the other door in order to open or close the doors simultaneously.
- 20 The shelf 8 and upper cross bar 7 of the interior frame connected with the side stiles of the latter, as has been stated, serve also to brace said stiles and consequently the inner frame between the ends thereof.
- 25 The front of the top pocket of the frame will be properly covered by the front wall of the chute down to the cross bar 7, and the front of the bottom pocket of said frame will be properly covered by the front wall 30 of the chute up to the shelf 8 so that said openings will not appear in front.
- Having thus described my invention what I claim as new and desire to secure by Letters Patent is:—
- 35 1. A dumb waiter having an exterior frame composed of angular-side pieces, a cap, and a sill, vertically extending channel-shaped guides mounted in said frame, means for connecting said guides with said frame, 40 slideable doors mounted in the said guides,

the length of said frame and guides being greater than the combined height of the doors in closed position forming pockets respectively at the top and bottom of said frame to receive said doors respectively in 45 the open position thereof, ears on the lower door extending laterally therefrom and passing freely through the central walls of said guides, and flexible members attached to said ears adapted to pass over pulleys on 50 said guides and to be connected with the upper door.

2. A dumb waiter having an exterior frame composed of angular-side pieces, a cap, and a sill, vertically-extending channel-shaped guides mounted in said frame; means for connecting said guides with said frame, 55 slideable doors mounted in the said guides, the length of said frame and guides being greater than the combined height of the 60 doors in closed position, forming pockets respectively at the top and bottom of said frame to receive said doors respectively in the open position thereof, ears on the lower door extending laterally therefrom and 65 passing freely through the central walls of said guides, flexible members attached to said ears adapted to pass over pulleys on said guides and to be connected with the upper door, a cross bar at the base of the 70 upper pocket, and a shelf at the top of the lower pocket, said shelf and cross bar having their ends connected respectively with said channel-shaped guides and serving also to brace the latter between their ends.

EDWARD W. DUGDALE.
